UNITED STATES PATENT OFFICE

155,438

DESIGN FOR A BEVERAGE SERVING
UTENSIL

Peter Muller-Munk, Pittsburgh, Pa., assignor to Ekco Products Company, Chicago, Ill., a corporation of Illinois

Application April 20, 1948, Serial No. 145,844

Term of patent 7 years

(Cl. D44—1)

To all whom it may concern:

Be it known that I, Peter Muller-Munk, a citizen of the United States, residing at Pittsburgh, county of Allegheny, State of Pennsylvania, have invented a new, original, and ornamental Design for a Beverage Serving Utensil, of which the following is a specification, reference being had to the accompanying drawing, forming part thereof.

Fig. 1 is a side elevational view of a beverage serving utensil, showing my new design.

Fig. 2 is a side elevational view when viewed from the right side of Fig. 1.

Fig. 3 is a top plan view.

The dominant feature of the design resides in the portion shown in full lines.

I claim:

The ornamental design for a beverage serving utensil, as shown and described.

PETER MULLER-MUNK.
